CLAIM

The ornamental design for a PC card adapter, as shown and described.

DESCRIPTION

FIG. 1 is a perspective view of a PC card adapter according to one embodiment.

FIG. 2 is a top view of the PC card adapter of FIG. 1.

FIG. 3 is a bottom view of the PC card adapter of FIG. 1.

FIG. 4 is a proximal end view of the PC card adapter of FIG. 1.

FIG. 5 is a distal end view of the PC card adapter of FIG. 1. FIG. 6 is a right side view of the PC card adapter of FIG. 1; and,

FIG. 7 is a left side view of the PC card adapter of FIG. 1.

The rectangular space to the right of the logo label is a hollow window.

The broken lines are for purposes of illustration only and form no part of the claimed invention.
